REISSUED

UNITED STATES PATENT OFFICE

HAROLD E. BALSIGER, OF WAYNESBORO, PENNSYLVANIA, ASSIGNOR TO LANDIS TOOL COMPANY, OF WAYNESBORO, PENNSYLVANIA, A CORPORATION OF PENNSYLVANIA

SAFETY DEVICE FOR GRINDING MACHINES

Application filed June 13, 1928. Serial No. 285,113.

This invention relates to safety devices for use with an hydraulically operated work rest on grinding machines, and particularly crank grinding machines.

It is an object of the invention to provide safety means whereby the work carriage on the grinding machine cannot be traversed while the work rest is in position to support the work.

10 A further object is to provide in a safety combination of the above character, an automatic pressure operated fluid by-pass valve.

A further general object is to provide a safety device in grinding machines or the like 15 which will require as little attention from an operator as possible without danger of injury to the machine.

Further objects and advantages will become apparent as the description proceeds.

20 Referring to the accompanying drawings, which are made a part hereof and on which similar reference characters indicate similar parts,

25 Figure 1 is a partial end elevation, partly in section, of a crank grinder equipped with a stationary hydraulic back rest, and showing the safety device in its relation to the grinder,

Figure 2 is a sectional front elevation of the by-pass valve, and

Figure 3 is a sectional elevation of the piston which operates the work rest.

The crank grinding machine of which my invention is here shown as forming a part, is the machine described in a co-pending application of Amos P. Steiner, Paul Stoner and Charles P. Harrison, Serial No. 126,583, filed August 2, 1926, for crank grinding machines, and the back rest is that described in the application of Amos P. Steiner and Harold E. Balsiger, Serial No. 143,248, filed October 21, 1926, for hydraulic back rests for grinding machines. The grinding machine and the back rest will therefore be described only insofar as is necessary to understand the application of the control device to these machines.

In the drawings numeral 10 indicates the base of a grinding machine having a traversable carriage 11 slidably mounted in suitable guideways thereon. The traverse carriage is

reciprocated by means of a rack 12 mounted thereunder, which is driven by a suitable pinion 13 which pinion is operated by means of an oscillating motor 14. The motor is driven by pressure fluid delivered thereto through a pipe 15. The work 16 is mounted in a well known way upon the traverse carriage in position to be moved to grinding position before an abrasive wheel 17. The work rest consists of a back rest bracket 18, secured upon the base of the machine. A slide member 19 carrying a work engaging jaw 20 is moved toward and from working position by means of a pinion 21 engaging the rack teeth 22 on the lower part of the slide 19. A small pinion 23 is connected to the large pinion 21 and is driven by means of rack teeth 24 on a piston rod 25. The piston rod carries on its lower end a piston 26 which moves in a cylinder 27. Pipes 28 and 29 provide inlet and outlet passages to the cylinder 27. A reversing valve 30 admits pressure fluid selectively below or above the piston 26 to move the work engaging jaw to operative position, or withdraw it from operative position. A lower work engaging jaw 31 is pivoted at 32 and is moved to operative position by means of a plunger 33 which is connected to a plate 34 secured to the back rest slide 19. The details of the reversing valve 30 have not been shown because any conventional structure for admitting fluid above and below piston 26 and for exhausting fluid from the cylinder 27 may be used.

Connected with a chamber above the piston 26 in the cylinder 27 is a pipe 35. This pipe connects with a by-pass valve shown as a whole at 36, and which forms the control or safety feature of the invention. The details of this valve will now be described:

The valve comprises a valve casing 37 having a double piston 38 and 39 reciprocably mounted in a bore therein. The piston 39 is longer than the piston 38, and is provided with a flange 40 which engages a shoulder in the cylinder valve body to limit the movement of the valve in one direction. A cap 41 is screwed into the end of the valve casing and has a hole 42 therethrough, into which is threaded a connection on the pipe 35. A

spring 43 positioned between one end of the piston 38 and a disc 44 exerts pressure upon the valve piston to force it to the right as shown in Figure 2. A cap 45 closes 5 one end of the bore in the casing 37. This cap has an adjusting screw 46 threaded therethrough and engaging the disc 44 to provide means for adjusting the tension of the spring 43. The valve casing is provided with 10 an inlet port 47 and a discharge port 48. A pipe 49 connects the discharge port with suitable connections leading to the reservoir in the base of the grinding machine, not shown. A relief port 50 provides for leakage of fluid 15 past the piston 38. The port 47 is connected by means of a short pipe 51 with the pipe 15 which supplies motive fluid to the oscillating motor 14. The tension of the spring 43 is such that it requires greater pressure to operate the by-pass valve than the work rest. The valve will therefore not be operated while the back rest is being withdrawn, nor until the piston has reached its lowermost position.

25 The operation of the device is as follows: When the piston 26 is in the above position shown in full lines in Figure 1, the chamber above the piston is open to the high pressure fluid line 28. The pipe 35 in communication 30 with the high pressure fluid chamber delivers pressure through the passage 42 against the end of the piston 39 to force it to the left, as shown in Figure 2, against the tension of the spring 43. This holds the plunger in the 35 position shown in full lines in Figure 2, and closes communication between the ports 47 and 48. High pressure fluid in the pipe line 15 will therefore be delivered to the oscillating motor 14 to drive the traversing carriage 40 11. When, however, the reversing valve 30 has been moved to admit high pressure fluid below the piston 26 and to exhaust it above 45 the piston 26, the piston will be moved upward to move the back rest to operative position in engagement with the work 16, as shown in dotted lines in Figure 1. When the reversing valve is in this position, pressure fluid is allowed to exhaust through the reversible valve 30 to the pipe 29. This shifting 50 of the reversing valve relieves pressure at the right of the flange 40 on the piston 39 and allows the spring 43 to move the piston to the position shown in dotted lines in Figure 2. High pressure fluid from the pressure lines 55 15 will then escape through the pipe 51, the ports 47, 48 and outlet passage 49, to a reservoir in the base of the machine. This relieves the pressure in the pipe line 15 and renders the traversing motor 14 inoperative. This 60 provides a safety against accidental attempts to traverse the work carriage while the stationary back rest is in a position to support the work. The advantages of the device in contributing a step toward making a machine 65 more nearly fool-proof should be apparent.

It will be obvious to those skilled in the art that various changes may be made in my device without departing from the spirit of the invention, and I, therefore, do not limit myself to what is shown in the drawings and described in the specification, but only as set forth in the appended claims.

Having thus fully described my said invention, what I claim as new, and desire to secure by Letters Patent, is:

70 1. In combination, a grinding machine, a work carriage on said machine, an abrasive wheel, a work rest adapted to support the work against the pressure of the abrasive wheel, means for reciprocating the work carriage, means for moving the work rest to and from operative position, and means controlled by the movement of said work rest to render the said carriage reciprocating means operative or inoperative, substantially as set forth.

75 2. In a grinding machine having a hydraulically operated work rest and a hydraulically traversed work carriage, means for traversing the work carriage, and means controlled by movement of the work rest for rendering the said traversing means operative or inoperative, substantially as set forth.

80 3. In a grinding machine a work carriage, a fluid motor for driving said carriage, a high pressure fluid line to said motor, a pressure operated by-pass in said fluid line, a fluid operated back rest movable into and out of operative position, and means for opening said by-pass when said work rest is in operative work engaging position, substantially as set forth.

85 4. In a grinding machine a work carriage, a motor for traversing said carriage, a high pressure motive fluid line connected to said motor, a by-pass valve in said line, a work rest, hydraulic means for moving said back rest into and out of operative position, and connections from said hydraulic means to said by-pass whereby said by-pass will be opened when said work rest is in operative work engaging position, substantially as set forth.

90 5. In combination a grinding machine having a hydraulically operated work rest, a hydraulic carriage traverse, and interconnected means to prevent traversal of the work carriage when the work rest is either in motion or is in operative position, substantially as set forth.

95 6. In combination a grinding machine, a hydraulically operated carriage traverse, a source of pressure fluid, a by-pass valve in the pressure line between said traverse operating means and said source of pressure, a fluid pressure operated piston for operating the work rest, fluid connection from said work rest to said by-pass valve whereby said by-pass will open when the pressure is released.

on one side of the piston, substantially as set forth.

7. In combination a grinding machine, a hydraulically operated carriage traverse, a source of pressure fluid, a by-pass valve in the pressure line between said traverse operating means and said source of pressure, a fluid pressure operated piston for operating the work rest, fluid connection from said work rest to said by-pass valve, whereby said by-pass will close when pressure is exerted on one side of the piston, substantially as set forth.

8. In a grinding machine a hydraulically operated work rest, a hydraulically operated carriage traversing mechanism, a high pressure fluid line from a source of pressure fluid for operating the said work rest and the said traversing mechanism, a by-pass valve in said high pressure fluid line, a connection between the said work rest and the said valve whereby pressure fluid is directed to the carriage traversing mechanism or is by-passed from the high pressure fluid line depending on the position of the work rest, substantially as set forth.

In witness whereof, I have hereunto set my hand at Waynesboro this 8th day of June, A. D. nineteen hundred and twenty eight.

HAROLD E. BALSIGER.
